UNITED STATES PATENT OFFICE.

ROBERT LAW, OF TOLEDO, OHIO;

TIE-PLATE.

949,907.

Specification of Letters Patent. Patented Feb. 22, 1910.

Application filed October 5, 1908. Serial No. 456,105.

To all whom it may concern:

Be it known that I, ROBERT LAW, a citizen of the United States, residing at Toledo, in the county of Lucas and State of Ohio, have 5 invented a new and useful Improvement in Tie-Plates, of which the following is a specification.

My invention relates to a tie plate, and has for its object to provide a light, strong, 10 durable, and economical plate for railway ties, that is adapted for better securing a rail to a tie and prevent the rail from "spreading"; to protect the spikes and the tie from the wear of the rail; that is adapted 15 to be inserted between the tie and the rail without loosening the rail from the next adjacent ties and that is self seating and self leveling on a worn tie. I accomplish these objects by constructing a tie plate as hereinafter described and illustrated in the 20 drawings in which—

Figure 1 is a top view of a tie plate constructed in accordance with my invention. Fig. 2 is a longitudinal section of the same 25 on line A—A, with a rail, tie, and spike indicated by dotted lines. Fig. 3 is an enlarged cross section of the same, (partly broken away), on line B—B, and Fig. 4 is a perspective view of the same.

30 In the drawings, 1 designates a tie plate constructed in accordance with my invention, and is formed from a wrought metal plate of suitable dimensions, and provided,— by being compressed in a suitable punch 35 and forming die,—with the hollow bosses 2, projecting from the top of the plate, suitable for receiving the spikes that secure the rail and the plate to the tie, and located to form abutments 3 on opposite sides of the 40 rail base, engaging the flanges. The plate thus formed, being flat on its under face, is held firmly secured to the tie by the spikes 4, which are driven through the hollow bosses 2, into the tie 5, with the heads of the 45 spikes engaging the flanges of the rail 6. Thus secured, the wear caused by the lengthwise movement of the rail,—produced by the motion of the trains or by expansion or contraction of the rail,—is received by the 50 plate instead of the tie and the spikes, and lateral pressure on the rail in either direction, is resisted equally by the spikes on both sides of the rail, thereby increasing the security of the rail against spreading.

55 To adapt my tie plate for convenient application to established tracks, without re-

moving or raising the rail, I have provided it on the one side with the bevels 7, forming the cutting edges 8 on the end portions of one side edge of the plate, that extend beyond the outer edges of the rail flanges. The cutting edges 8 are in the plane of the bottom face of the plate, and between the cutting edges, the portion 9 of the plate is rounded or beveled on the under side. Thus 60 constructed, when it is desired to use the plate on a tie which has a channel worn in its top face by the rail base, after removing the spikes from the tie, the plate is placed underneath the rail with the hollow bosses 65 on opposite sides of the rail flanges and its top face engaging the bottom of the rail base, and with the edges 8 engaging the side of the tie at the level of the bottom of the worn channel. Being thus located, the plate 70 is driven between the tie and the rail base, the bosses 2 forming directing guides, and as the plate is driven between the tie and the rails, the edges 8 cut away the portion of the wood of the tie along the sides of the channel, so that the plate when in its proper 75 position on the tie, is firmly seated thereon.

Where the tie is not worn by the rail, the plate may in like manner be introduced between the rail and the tie, as the rounded 80 central portion 9 of the plate will wedge between the tie and the rail and prevent the edges 8 from cutting into the wood of the tie.

By forming in a punch press as described, a pair of hollow bosses 3 on each end portion 85 of the plate, the plate is not only provided with abutments to prevent lateral movement of the rail independent of the plate, and with a plurality of spike holes on each side of the rail, but the plate is thereby greatly 90 strengthened against buckling, without increasing the weight of the plate. The plate thus provided with hollow bosses is also without the tendency,—which is very commonly incident to plates having transverse 95 ribs forming rail abutments,—to break along the inner side of the abutments, or through the spike holes, which as commonly constructed constitute their points or lines of greatest weakness, whereas, in my construction, the bosses 2, which provide the spike 100 holes of my tie plate, greatly increase its strength. They also prevent access of water through the spike holes to the tie immediately around the spike, and the decay of the 110 tie and the loosening of the spike therein, commonly arising therefrom.

What I claim to be new is—

1. A tie plate comprising a wrought metal plate having formed on each end portion thereof by being struck up in a punch and die press, a plurality of tubular bosses projecting from the upper face of the plate in position to form abutments for engaging each side of a rail base, and adapted to receive spikes for securing the rail to the tie, 10 said plate having both the upper and lower faces otherwise plain surfaces.

2. A tie plate for railways, comprising a wrought metal plate, having formed on each end portion a pair of hollow bosses, adapted 15 to engage and form abutments for the flanges of a rail base, and to receive spikes

for securing the plate to a tie, and a rail on the plate, said plate having downward bevels along one side edge, forming cutting edges on the end portions of the plate extending beyond the outer edges of the rail base, and an upward bevel between the cutting edges, substantially as and for the purpose set forth. 20

In witness whereof I have hereunto 25 signed my name in the presence of two subscribing witnesses, this 21st day of September, 1908.

ROBERT LAW.

In presence of—
M. F. GRIFFIN,
M. KESSLER.
